UNITED STATES PATENT OFFICE.

MARY THRASHER, OF NASHVILLE, TENNESSEE.

ADJUSTABLE NECKWEAR.

Application filed January 9, 1924. Serial No. 685,192.

To all whom it may concern:

Be it known that I, MARY THRASHER, citizen of the United States, residing at Nashville, in the county of Davidson and State of Tennessee, have invented certain new and useful Improvements in Adjustable Neckwear, of which the following is a specification.

This invention relates to collars, of lace, 10 linen fabric or the like, which are intended for use on ladies' dresses and which are manufactured separately from the dresses to be attached to the dress by the wearer; the invention having for an object the provision of a novel collar of this type which 15 is adjustable so as to fit dresses having varying shapes of neck opening or of varying length around said neck opening.

Hitherto the fact of the lack of adjustability of these collars has been a considerable drawback in the marketing thereof since the retailers have to carry an excessively large stock, the excess of which has frequently to be disposed of at a loss. This 25 difficulty I have obviated by my novel collar construction which renders any given collar readily adjustable to fit different dresses.

For further comprehension of the invention and of the objects and advantages thereof, reference will be had to the following description and accompanying drawing, and to the appended claims in which the various novel features of the invention are more 35 particularly set forth.

Fig. 1 of the drawing is a face view showing my improved collar as ready for attachment to a dress.

Fig. 2 is a transverse sectional view taken 40 on the line 2—2 of Fig. 1.

Fig. 3 is a similar view to Fig 1 but showing a slightly modified construction.

Fig 4 is a transverse sectional view of this modified form of collar this view being taken 45 on the line 4—4 of Fig 3, but showing the inner edge as arranged when attached to the neck of a dress.

In constructing my improved collar I provide two straight pieces 10 of suitable material which may be of linen fabric, or lace or a combination of the two and of any desired ornamental design. As here shown the body 10 of each piece is composed of a suitable fabric, and is edged on one side 50 and on each end with lace 10^a. These pieces

may be of any suitable size, a length of eighteen inches and a width of four or five inches having been found suitable. The other edge of each piece is hemmed down as at 10^b to provide a longitudinally extending recess through which a narrow tape 13 is run, the one tape extending through both pieces which are thus strung on the tape, the ends of the tape extending beyond the ends of the said pieces. This tape enables 65 the two pieces to be readily drawn up or contracted in length to fit the collar to the neck of the dress, the collar then being in the form of a ruffle. The collar can then be readily pinned onto the neck of the dress 70 and later basted in place.

With this arrangement, as will be apparent, the collar of this type is rendered more salable, since the prospective purchaser is not in any doubt as to the possibility of 75 fitting the collar upon the dress to which she may contemplate applying it.

In Figs. 3 and 4 I have shown a further development of my invention in which a pair of recesses are formed along the inner edge of each piece by hemming down the said edge as at 10^c. In the recess immediately adjacent the edge an elastic tape 15 is placed, while the usual fabric tape 13 is placed in the other recess, the two 80 tapes being attached to the pieces 10 at the joint ends of the latter only. In applying this collar the elastic tape can be stretched or tensioned and then secured along its length to the said pieces by basting stitches 85 so that when released it draws the said pieces evenly to ruffled form from end to end of the latter. When the collar is attached in place the inner edge portion is folded behind the collar as shown in Fig. 4 90 of the drawing, and after the collar has been secured in place by an initial line of stitches passed therethrough below the turned back portion, the basting stitches referred to may be removed to free the elastic 95 tape, and the upper edge of the collar stitched in place. This top edge portion may if desired be folded inside the neck of the dress.

Having thus described my invention what 105 I claim as new and desire to protect by Letters Patent of the United States is as follows:—

1. A collar of the type described comprising two separate pieces of material each 110

formed with a recess extending along the upper edge thereof, and a single tape member passed through said recesses.

2. A collar of the type described comprising two separate pieces of material each formed with a recess extending along the upper edge thereof, and a single tape member passed through said recesses, and serving as the connecting medium of the two

10 pieces.

3. A collar of the type described comprising two separate pieces of material each formed with a recess extending along the upper edge thereof, and a single tape member passed through said recesses, and serving as the connecting medium of the two pieces, the said tape being secured to the said pieces at the two adjacent ends of the latter only.

4. A collar of the type described comprising separate pieces of material each formed with a pair of recesses extending along the upper edge thereof, and elastic tape extending through one recess, and an inelastic tape extending through the other

25 recess.

5. A collar of the type described comprising separate pieces of material each formed with a pair of recesses extending along the upper edge thereof, and elastic tape extending through one recess, and an inelastic tape extending through the other recess, said tapes being connected to the said pieces at the two adjacent ends of the latter only.

6. A collar of the type described comprising separate pieces of material each formed with a pair of recesses extending along the upper edge thereof, and elastic tape extending through one recess, and an inelastic tape extending through the other recess, said tapes being connected to the said pieces at the two adjacent ends of the latter only, one of the said recesses being closer to the inner edge than the other, and the elastic tape being located in the said recess.

In testimony whereof I have affixed my signature.

MARY THRASHER.
